UNITED STATES PATENT OFFICE.

DAVID W. ERNST, OF FLEMINGTON, NEW JERSEY.

TRANSMISSION BAND.

Application filed May 19, 1925. Serial No. 31,372.

To all whom it may concern:

Be it known that I, DAVID W. ERNST, a citizen of the United States, residing at Flemington, in the county of Hunterdon 5 and State of New Jersey, have invented certain new and useful Improvements in Transmission Bands, of which the following is a specification.

My invention relates to Ford transmission 10 bands.

My object is to provide a device of this character which can be formed from old, or second-hand Ford parts, and therefore be made cheaper than is possible to make devices intended for the same purpose, when 15 so constructed that they have to be made from new material.

Another object is to provide a device of this character which, within itself, is of 20 very cheap and easy construction, even though new materials be used in making it.

Still another object is to provide a device in which the ear and band will have prolonged and accentuated frictional engagement 25 with each other when the two are being disengaged, one from the other, but nevertheless so constructed that the initial disengaging movement is comparatively easy.

Minor objects will appear in the subjoined description.

The invention consists in certain novel features of construction and arrangement of parts, as will be hereinafter described and 35 claimed, reference being had to the accompanying drawings, in which;

Fig. 1 is a perspective view showing the band and ear removably held in operative relation to each other.

Fig. 2 is a vertical section showing the parts in the same position as illustrated in Fig. 1; and,

Fig. 3 is a sectional view showing the parts in the position they occupy while in 45 the process of being disengaged from each other.

The numeral 1 indicates the brake band, 2 the brake lining carried thereby, and 3 the ear.

The brake is rigidly secured to the under or concave face of the brake band by means of the brass rivets 4 and 5 which have flat rounded heads 4^a and 5^a respectively. The brake band also carries three 50 steel rivets 6, 7, and 8, located between the rivets 4 and 5, and approximately equidis-

tant from each other; and these steel rivets have strong flat heads 6^a, 7^a, and 8^a, respectively. The ear 3 has openings 9, 10, and 11, adapted to easily receive the heads 6^a, 7^a and 8^a, and these openings have rearwardly extending slots 9^a, 10^a, and 11^a, of a width to easily receive the shanks of the rivets 6, 7, and 8.

The brass rivet 4 is so positioned in the band, as to bring its head 4^a into registration with the opening 9 when the ear and band are brought into operative relation to each other, so that when a reverse movement of the ear is attempted, the said head 4^a offers a certain degree of resistance thereto.

It will also be noticed that the brass rivet 5 is located only slightly beyond the end of the ear, so that as soon as the ear is moved sufficiently toward the left on the band 1 to bring the bottom of the ear up onto the head of the rivet 4, the tail end of the ear begins to ride up on the head of the rivet 5, and then the ear is held up on the heads of the two rivets—one at each end of the ear till the rivets 6, 7, and 8, come into registration with the openings 9, 10, and 11, which permits the ear and band to become suddenly disengaged. This arrangement keeps the ear and band from becoming loose on each other till the parts have reached the point where they can be entirely disengaged. But the fact that the ear rides up on the head of the rivet 4 before the rivet 5 is engaged, makes the initial disengaging movement of the ear much easier.

The brake band 1 is provided at its forward end with a little upturned ledge or section 12, which along with the shanks of the rivets 6, 7, and 8, serves as a stop for limiting the movement of the ear to the right. A screw driver can be inserted between this ledge and the end of the ear for making the initial movement of the ear on the brake band, when it is desired to disengage the two. The resiliency of the band 1 permits the ear to ride up on the heads of the rivets 4 and 5. In Fig. 3 of the drawings, the shanks of the rivets 6, 7, and 8, are shown longer than they actually are in practice; but this showing is made in order to accentuate the fact that the ear is yieldingly held for a prolonged period in binding engagement with the brake band till the two are brought in position to be entirely disengaged from each other. Thus

it will be seen that the brass rivets 4 and 5 are made to serve two very important purposes: first, to hold the brakes on the bands, and secondly, to yieldingly hold the ear in 5 vigorous and prolonged engagement with the band.

Making the rivets 4 and 5 of brass has this advantage, that they do not become corroded, and then the iron moves over them 10 somewhat easier than if they were iron anyhow.

The operation of the device is fully apparent from the above description.

From the foregoing it will be seen that I 15 have provided a device of very simple, effective, and inexpensive construction, which, with the exception of the rivets, can be easily and quickly made from second hand Ford parts.

20 The upturned end 12 at the forward end of the band forms an abutment which relieves the strain upon the rivets 6, 7, and 8, and causes the device to last longer.

Having now described my device, what I 25 claim as new and desire to protect by Letters Patent is:—

1. A device of the character described, comprising a band and ear for removable engagement with each other; and a brake lining designed to be carried by the band, the band having brass rivets extending downwardly for engagement with the brake lining to hold the same rigidly on the band; and having upwardly extending steel rivets 30 for sliding engagement with the ear to removably hold the same on the opposite side of the band; said ear having openings enlarged at one end for the reception of the heads of the steel rivets, and having narrow 35 portions extending rearwardly from said openings and adapted to receive the shanks of said steel rivets; one of said brass rivets being arranged to register with the enlarged 40 portions extending rearwardly from said openings and adapted to receive the shanks of said steel rivets; one of said brass rivets being arranged to register with the enlarged

portion of the forward one of said enlarged openings in the ear, with the head of the 45 rivet projecting into said opening when the ear and band are in their normal position relatively to each other; whereby to cause said rivet head to form an obstruction to the movement of the ear on the band. 50

2. A device of the character described, comprising a band and ear for removable engagement with each other; and a brake lining designed to be carried by the band, the band having brass rivets extending 55 downwardly for engagement with the brake lining to hold the same rigidly on the band; and having upwardly extending steel rivets for sliding engagement with the ear to removably hold the same on the opposite side 60 of the band; said ear having openings enlarged at one end for the reception of the heads of the steel rivets, and adapted to receive the shanks of said steel rivets; one of said brass rivets being arranged to register 65 with the enlarged portion of the forward one of said enlarged openings in the ear, with the head of the rivet projecting into said opening when the ear and band are in their normal position relatively to each other; whereby to cause said rivet head to form an obstruction to the movement of the 70 ear on the band; the other brass rivet being located in near proximity to the rear end of the ear to engage the same after its initial rearward movement; whereby when the front end of the yoke rides up on the first named rivet, the rear end of the ear begins riding up on the rear rivet; to cause both rivets to be in engagement with the 75 ear, one at each end thereof, during all except the initial part of the disengaging movement of the ear on the band. 80

In testimony whereof I affix my signature.

DAVID W. ERNST.
